UNITED STATES PATENT OFFICE.

WILLIAM ELLIS MAY, OF LONDON, ENGLAND, ASSIGNOR TO THE ELLIS MAY VACUUM STEEL SYNDICATE, LIMITED, OF SAME PLACE.

APPARATUS FOR CASTING METALS.

SPECIFICATION forming part of Letters Patent No. 633,326, dated September 19, 1899.

Application filed August 12, 1897. Serial No. 648,061. (No model.)

To all whom it may concern:

Be it known that I, WILLIAM ELLIS MAY, a subject of the Queen of Great Britain, residing at Bromley, London, in the county of Kent, England, have invented new and useful Improvements in Apparatus for Casting Metals, (for which I have obtained patents in France, No. 264,642, dated March 3, 1897, and in Belgium, No. 126,877, dated March 10, 1897,) 10 of which the following is a specification.

My invention consists in the novel features hereinafter described, reference being had to the accompanying drawings, which illustrate one form in which I have contemplated embodying my invention, and said invention is 15 fully disclosed in the following description and claims.

In the said drawings, Figure 1 is a plan view of an apparatus for casting metal embodying 20 my invention, a part of the top of the vacuum-chamber being removed. Fig. 2 is a vertical section of the same on line 2 2, Fig. 1. Fig. 3 is a section on line 3 3 of Fig. 2, drawn to a larger scale.

25 *a* represents the vacuum-chamber, which is preferably sunk in the ground to a depth equal to the height of the sides of the chamber and having a pipe *a'* connected therewith, leading to a vacuum-producing apparatus 30 (not shown) for creating a working vacuum in said chamber. The pipe *a'* is provided with a valve *a''*, controlling the same.

35 *b* represents the removable top of the vacuum-chamber, which is provided with flanges *c c*, which rest upon similar flanges formed on the side walls of the chamber, and packing *d* is placed between said flanges to form an air-tight connection. The weight of the top or cover *b* is sufficient to hold it in place, and 40 when the air is exhausted from the vacuum-chamber there is an additional pressure of the atmosphere thereon of fifteen pounds to the square inch, so that no means for holding the cover in place are essential.

45 *b' b'* are glazed sight-holes in the top or cover *b* to enable the operation proceeding within the vacuum-chamber to be observed.

50 *f* is a ladle for containing the molten metal before it is run into the mold, the said ladle being located outside of the vacuum-chamber and having a discharge-aperture *f'* communicating with said chamber, said aperture being closed normally by a plug or valve *f''*,

which is raised by suitable mechanism, as by hand-levers *f''*. (See Fig. 3.)

55 The vacuum-chamber *a* is provided adjacent to the top with a laterally-extending recess or vestibule *a''*, the upper part of which is provided with a circular aperture *a''* to receive the ladle *f*, said aperture being surrounded by a horizontal flange *a''*. The side walls of 60 ladle *f* are provided with a horizontal flange *f''* to engage the flange *a''*, and packing may be inserted between the flanges to produce a tight joint. No fastening means are required 65 to secure the flanges together, owing to the weight of the ladle and, further, the atmospheric pressure thereon when the air is exhausted from the vacuum-chamber *a* and its vestibule *a''*.

70 *h* is a runner or trough extending from the discharge-aperture of the ladle within the vacuum-chamber to the inlet-aperture of the mold.

75 *i* is the mold, which in this instance is adapted for the casting of armor-plate and consists of four blocks or plates so placed as to form a rectangular cavity within the same, said blocks *j j* being clamped together by cross-plates *j' j'* on opposite sides of the mold 80 and bolts *j'' j''* connecting said plates. The bottom *m* of the vacuum-chamber is preferably inclined, so that the mold will be supported in an inclined position. The mold is open at both ends and is provided with an 85 inlet *k'* at its highest point for the admission of the molten metal and for the expulsion of the impurities thereof, as hereinafter described. The end of the mold farthest from the inlet is closed by a head *k''*, which is operatively connected by means of a piston-rod *l* with a hydraulic or other press *l'*, by means 90 of which the head can be moved along the bottom of the vacuum-chamber to the end of the mold. At the opposite end of the mold 95 is a plunger *k*, working in the mold and closing the end of the same adjacent to the inlet, so that the molten metal enters the mold immediately in front of the plunger. The plunger *k* is connected with the piston of a 100 hydraulic or other press *n*, and said press *n* is connected by rods *n'* with the head *k''*, said rods extending through apertures in said head. Each of the rods *n'* is provided near 105 its end with a series of annular undercut grooves, as indicated at *n''*, Figs. 1 and 2, and

the rear face of the head k^2 is provided with a pair of separable vertically-movable clamping-blocks $n^3 n^3$, surrounding each of said rods n' . These clamping-blocks are each recessed 5 to fit around half of the rod n' and provided with annular projections for engaging and interlocking with the annular grooves n^x . On each side of the head k^2 I provide a pair of vertically-disposed screw-shafts $n^4 n^4$, extending downward through two pairs of clamping-blocks $n^3 n^3$ and having oppositely-threaded portions $n^5 n^5$, engaging suitably-threaded apertures in the blocks of each pair. The upper end of each screw-shaft n^4 is provided with a pinion n^6 , and between the pinions $n^6 n^6$ of each pair of shafts $n^4 n^4$ is a driving-pinion n^7 on a driving-shaft n^8 , which is operated by arms $n^9 n^9$ or equivalent mechanism. By turning one of the driving-shafts 10 n^8 the two adjacent screw-shafts $n^4 n^4$ will be rotated, thereby causing the pairs of clamping-blocks actuated thereby to close upon the rods $n' n'$ or to recede therefrom. When it is desired to adjust the head k^2 , the arms n^9 will 15 be operated to rotate the driving-shafts $n^8 n^8$, so as to release all the pairs of clamping-blocks from the rods $n' n'$, when the head can be moved longitudinally, as desired, on the bottom of the vacuum-chamber. After adjusting the head the pairs of clamping-blocks 20 will be caused to come together around the grooved portions of the rods $n' n'$, thus securely locking the head against outward movement.

18 This mechanism constitutes an adjusting device for the head k^2 , which operates in conjunction with the auxiliary press l' , and by means of this adjusting mechanism and the rods n' the head is rigidly secured with respect to the main press n .

25 When the casting is run, the ladle f is filled with molten metal, the air is exhausted from the vacuum-chamber, and the plug f^2 is lifted to allow the metal to flow into the runner h and thence to the inlet k' of the mold. The 30 foreign gases in the metal and any air carried in with it will escape into the vacuum-chamber and be withdrawn therefrom, so that there can be no bubbles in the completed casting. When the mold is full, the impurities in the metal, which are lighter than the metal itself, will accumulate in front of the plunger adjacent to the inlet of the mold. The main press n is then operated, and as the 35 plunger k moves inward it displaces and forces out through the inlet a portion of the molten metal, thus driving out all of the impurities, and when the plunger has moved a short distance it will have closed the inlet of the mold. The pressure of the plunger is continued and the metal is compressed to an extent equal to the amount which it will contract while cooling. The casting is then allowed to cool, and it will be found to be homogeneous in structure and absolutely free not 40 only from blow-holes, but also from impurities, and the tedious and expensive process of cut-

ting off the impure portions of the casting, which would otherwise be necessary, is entirely avoided, as the said impurities are 45 practically cut off while the metal is in a molten state, as heretofore described.

What I claim, and desire to secure by Letters Patent, is—

1. In an apparatus for casting metal, the 50 combination with a vacuum-chamber, of a mold located therein provided with an inlet for molten metal at its highest point, a movable plunger working in said mold located adjacent to said inlet and closing one end of 55 said mold, means for operating said plunger and means for introducing metal to said inlet from the outside of the vacuum-chamber whereby the gases in the molten metal will escape from the metal into said vacuum-chamber and the first movement of the plunger will expel the impurities in the metal 60 from the mold and close said inlet, substantially as described.

2. In an apparatus for casting metal, the 65 combination with a vacuum-chamber, of a mold located therein, having an open end and an inlet for the molten metal at the highest point of the mold, a plunger closing the open end of said mold, adapted to work in the 70 mold, and located adjacent to the said inlet, a ladle located outside the vacuum-chamber and having a discharge-opening within said chamber, a trough extending from said ladle, within said chamber, to the said inlet, whereby the gases in the molten metal will escape 75 therefrom into the vacuum-chamber before reaching the mold, and the impurities in the metal will collect at the highest part of the mold adjacent to the said inlet, and means 80 for operating said plunger to expel said impurities through the said inlet, to close said inlet and exert a compression upon the metal while it is cooling, equal to the contraction 85 of the metal, substantially as described.

3. In an apparatus for casting metal, the 90 combination with the vacuum-chamber, of a mold located therein open at both ends, and having an inlet for molten metal at its highest point, a head for closing the end of said mold 95 farthest from the said inlet, a plunger working in said mold and closing the end of the mold adjacent to the said inlet, means for introducing molten metal to said inlet from the outside of said mold, a main press for 100 operating said plunger, an auxiliary press for moving said head and adjustable connections between said main press and said head, whereby the gases in the molten metal will escape therefrom into the vacuum-chamber, 105 and the first movement of the said plunger will expel the impurities collecting adjacent to said inlet and close the inlet, substantially 110 as described.

WILLIAM ELLIS MAY.
